TURBINE-BLADING.

1,015,313.

Specification of Letters Patent. Patented Jan. 23, 1912.

Application filed August 6, 1908. Serial No. 447,229.

To all whom it may concern:

Be it known that I, JONATHAN S. GREEN, a citizen of the United States, and a resident of Pittsburgh, in the county of Allegheny and State of Pennsylvania, have made a new and useful Invention in Turbine-Blading, of which the following is a specification.

This invention relates to elastic fluid turbines and more particularly to blades for such turbines and has for an object the production of means for assembling turbine blades into blade segments.

In the drawings accompanying this application and forming a part thereof: Figure 1 is a fragmental section, taken longitudinally of the turbine, of a rotating blade-carrying element in connection with blades mounted in accordance with my invention; Fig. 2 is a section along the line A—A of Fig. 1; Fig. 3 is a fragmental plan view of a rotating blade-carrying element and blades secured thereto in accordance with my invention; and, Fig. 4 is a fragmental section, taken transversely of the turbine, of a stationary blade-carrying element and blades secured thereto in accordance with my invention.

In carrying out my invention I contemplate assembling the turbine blades into segmental blade rings and I employ a base strip for the blades which is formed in two separate parts. Each part of the compound base strip is provided with notches so arranged that the notches of one part cooperate with the notches of the other to receive and to secure in place the bases or roots of the blades. I also provide independent and separate means for positively and permanently locking each blade to the base strip and for permanently securing the separate parts of the strip together.

Referring to the drawings: a turbine blade-carrying element 6 is provided with a plurality of undercut and peripherally extending blade-mounting grooves 7, into each of which a base strip 8 is adapted to be secured by means of component wedges 9. Each base strip 8 is composed of two separate strips 10 which are curved to conform to the curvature of the mounting grooves adapted to receive them, and which are provided, across one face, with a plurality of radially-extending notches 13, of such shape and so spaced that the notches of one strip

cooperate with the adjacent notches of the other strip in receiving and securing in place the bases or roots of blades 14. The base or root of each blade is preferably swaged or otherwise formed to fit the notches 13 and each blade is secured in place by a co-operating pair of adjacent notches. A transversely extending notch 18 is provided on the convex face of the mounting portion or base of each blade. This notch, when the base of the blade is in place in a notch 13, registers with one of a plurality of cylindrical holes 16 which extend transversely through both of the strips 10 comprised in a base strip. Each hole 16 intersects one pair of co-operating notches 13 and is adapted to receive and hold in place a separate locking plug or pin 17, which is provided for each blade and which is adapted to co-operate with the notches 15 formed in the base of the blade and thereby positively lock it to the base strip. The plugs, to some extent, secure the separate strips of each blade-mounting ring together. I, however, find it preferable to countersink the outer ends of a few of the holes 16 in each strip as shown at 18, and to rivet over the ends of the plugs located in the countersunk holes and to thereby permanently secure the separate elements of the ring together and consequently the blades to the base strip.

The outer or free ends of each blade 14 is provided with a hole 19, which is comma-shaped in cross-section and through which a binding wire 20, of comma-shaped cross-section, is adapted to extend. After the blades are permanently secured to the base strips, the outer or free ends are properly spaced and rigidly locked in the proper relative positions by shearing and bending over, between adjacent blades, a longitudinally extending rib 21 which is formed integrally with the body portion of the wire 20. The sheared and bent over portions of the binding wire form separate spacing pieces which are located between adjacent blades and which positively hold the blades in their relative positions. The unsheared body portion of the wire binds the outer or free ends of the blades together.

The base strips are, for convenience, cut into segmental sections which are secured into the blade-mounting grooves 7 by means of the wedges 9, although any other suitable

means may be employed. One of the component strips 10 of each compound base strip is provided with an inclined face 22, the inclination of which corresponds to the 5 inclination of the undercut walls of the mounting grooves 7. The corresponding face of the other strip 10 is vertical; that is, is normal to the curved or peripheral faces of the strip.

10 In securing the base strips to the blade-carrying element, each compound base strip is introduced into a groove 7 and so located within the groove that its inclined face contacts with one of the undercut walls of 15 the groove. The segments are then secured in place by the wedges 9 which are preferably compound tapered wedges and which are introduced into the space between the vertical face of the strip and the adjacent 20 undercut wall of the groove. The compound tapered wedges are introduced into the groove in pairs and are so constructed that, when driven home, the two component wedges of each pair conjointly form a 25 wedge-shaped key which effectively secures the blade ring into the blade-mounting groove and which is prevented by its shape and the shape of its component wedges, from being dislodged from the groove by centrifugal or any other dislodging force. The 30 segments of the base strips are so arranged that they may be inserted into the blade-mounting grooves end for end without destroying the spacing of the blades. A number of pairs of wedges are employed to 35 secure each segment of the strip in the groove and are preferably so spaced within the grooves that the ends of the wedges of one pair abut against the ends of the wedges of 40 the next adjacent pair, and prevent any possibility of the wedges becoming displaced or loosened in the groove. The first and last pair of wedges introduced into the groove are in some suitable way prevented from 45 moving longitudinally and are thereby permanently locked into the slot.

Throughout the specification and claims I have utilized the word "blade" in its broadest sense, that is, to include both the rotating and the stationary blades, vanes or buckets of a turbine, and I have also employed the term "blade-carrying element" in its broadest sense; that is, to mean the rotating or stationary blade or bucket carrying 55 element of a turbine.

In accordance with the provisions of the patent statutes, I have described the principle

ple of my invention, together with the apparatus which I now consider to represent the best embodiment thereof, but I desire to 60 have it understood that the apparatus shown is only illustrative and that the invention can be carried out by other means.

What I claim is:

1. In combination with a plurality of 65 blades, a base strip for said blades and an independent locking pin extending transversely of said strip for securing one of said blades to said strip.

2. In combination with a plurality of 70 blades, a compound base strip comprising separate strips for receiving the bases of the blades, and separate locking pieces extending transversely of said strip for securing each blade to said base strip. 75

3. In combination with a plurality of blades, a base strip therefor and pins extending transversely of said strip for independently locking said blades to said strip.

4. In combination with a blade-carrying element provided with a blade-mounting groove, a plurality of blades, a compound base strip therefor, comprising two separate strips provided with coöperating notches adapted to receive the bases of the blades, and separate locking pieces extending transversely through said strips for securing each blade in place. 80

5. In combination with a plurality of 85 blades comprised in a row, a compound base strip for said blades comprising separate strips each provided with radially extending and coöperating notches for receiving the bases of said blades, and separate pieces extending transversely through each strip 95 for securing said strips together and each of said blades in place.

6. In combination with a plurality of 90 blades, a base strip for said blades and transversely extending locking pins, one for 100 each blade, to secure said blade to the strip.

7. In combination with a plurality of 105 blades, a base strip for said blades comprising two parallel members and locking pins, one for each blade, extending through the two members and engaging the blades.

In testimony whereof, I have hereunto subscribed my name this 4th day of August, 1908.

JNO. S. GREEN.
